UNITED STATES PATENT OFFICE.

JOHN RHINO, OF HECLA, MONTANA.

DOOR-SECURER.

SPECIFICATION forming part of Letters Patent No. 512,218, dated January 2, 1894.

Application filed August 15, 1893. Serial No. 483,214. (No model.)

To all whom it may concern:

Be it known that I, JOHN RHINO, a citizen of the United States, residing at Hecla, in the county of Beaver Head and State of Montana, 5 have invented a new and useful Door-Securer, of which the following is a specification.

My invention relates to a door securer, and has for its object to provide a simple, inexpensive, and efficient device capable of being 10 folded into a portable form whereby it may be carried in the pocket.

Further objects and advantages of this invention will appear in the following description, and the novel features thereof will be 15 particularly pointed out in the appended claims.

In the drawings: Figure 1 is a perspective view of a securer embodying my invention, with the parts arranged in the operative position. Fig. 2 is a similar view with the parts 20 arranged in the folded position. Fig. 3 is a sectional view, showing the securer applied in the operative position to a door. Fig. 4 is a detail view of the filler detached. Fig. 5 is 25 a similar view of the spur.

Similar numerals of reference indicate corresponding parts in all the figures of the drawings.

1 designates the main plate or body portion 30 of the securer, which is provided with a longitudinal series of threaded apertures 2, and a terminal transverse slot 3, and 4 represents a sharpened spur in the form of a blade which is provided at its back with an 35 upstanding flanged lug 5, adapted to engage the transverse slot in the main plate or body portion. The portions of the back of the spur 4, upon each side of the stud, form shoulders 6 which bear against the contiguous surfaces 40 of the plate, and the flange 7 of said lug engages over the opposite surface of the plate to retain the spur in position.

8 represents a stop-plate, provided with an enlarged front end or boss 9, which is adapted, when the device is in its operative position, to engage the edge of the door. Interposed between the contiguous surfaces of the stop-plate and main plate is a wedge-shaped filler 10, provided with a longitudinal central slot 11 to receive the shank 12 of a thumb-screw 13, which passes through a smooth perforation 14 in the stop-plate and engages one

of the threaded perforations 2 in the main plate. This thumb-screw is provided with a pivoted or hinged head 15, which may be 55 folded to occupy a minimum amount of space when the securer is detached from the door. The stop-plate is provided at its rear end with a perforation 17 and a cavity 18 which corresponds in shape and size with the spur 60 4, the latter being provided with a perforation 19 which registers with the perforation 17 when the spur, which is detachable from its seat in the main plate, is fitted in the cavity 18. 65

In Fig. 2, in which the device is shown in its folded form, the spur is arranged in the cavity 18 and is secured in place by the thumb-screw which engages said registering perforations, the slot in the filler, and one of 70 the threaded perforations in the main plate.

To apply the device to a door the spur is arranged in its seat in the main plate, as shown in Figs. 1 and 3, and the adjacent end of said main plate is inserted between the edge of the door and the opposite portion of the casing and the door is closed, thus forcing said spur into the casing. If the interval between the edge of the door and the casing is greater than the thickness of the main 80 plate, the tapered filler is employed to fill such additional space by inserting either its smaller or if necessary its larger end between the door and the main plate. The stop plate is now applied to the outer surface of the filler 85 with its enlarged end in contact with the surface of the door, and its perforation 14 is brought into alignment with one of the perforations 2 of the main plate, after which the thumb-screw is inserted in the registering perforations and the parts are secured firmly in 90 their adjusted positions.

Various changes in the form, proportion, and the minor details of construction may be resorted to without departing from the principle or sacrificing any of the advantages of 95 this invention.

Having described my invention, what I claim is—

1. In a door securer, the combination with a main plate carrying a spur, of a stop-plate, a thumb-screw engaging registering perforations in the stop-plate and main plate, and a slotted tapered filler interposed between the

stop and main plates and capable of adjustment, substantially as specified.

2. The combination of a main plate, a spur detachably secured to said plate, a stop-plate 5 provided with a cavity corresponding in shape and size with said spur and adapted to receive the same when detached from the main plate, and a thumb-screw engaging registering perforations in the main and stop plates 10 and adapted to secure the spur in the cavity of the stop-plate, substantially as specified.

3. The herein described door securer, comprising a main plate provided with a longitudinal series of threaded perforations and a 15 terminal transverse seat or slot, a spur provided with a flanged stud to engage said seat

or slot, a stop-plate provided with smooth perforations 14 and 17 and a cavity corresponding in shape and size to the said spur, a slotted filler interposed between the stop-plate 20 and the main plate, and a thumb-screw connecting said parts and adapted to secure the spur in the cavity of the stop-plate, substantially as specified.

In testimony that I claim the foregoing as 25 my own I have hereto affixed my signature in the presence of two witnesses.

JOHN RHINO.
